STEPHAN BLAZÉK, OF NEW YORK, N. Y., ASSIGNOR OF ONE-THIRD TO SAMUEL SHERMAN, OF NEW YORK, N. Y.

PERMUTATION-LOCK.

1,170,398.

Specification of Letters Patent.

Patented Feb. 1, 1916.

Application filed March 23, 1915. Serial No. 16,332.

To all whom it may concern:

Be it known that I, STEPHAN BLAZÉK, a citizen of the United States, and a resident of the city of New York, borough of Manhattan, in the county and State of New York, have invented a new and Improved Permutation-Lock, of which the following is a full, clear, and exact description.

The object of the invention is to provide 10 a new and improved permutation lock more especially designed for use on satchels, valises, trunks, doors and other articles and devices; and arranged to permit of engaging the keeper with the locking bolt irrespective of the permutation mechanism of the bolt and to prevent disengagement and unlocking unless a person is in the possession of the combination of the lock.

In order to produce the desired result, 20 use is made of a spring-pressed bolt and permutation mechanism for moving said bolt into retracted position, the bolt having movement wholly independent of the said controlling mechanism to allow of engaging 25 the keeper with the bolt at the time the controlling mechanism is in locking position.

A practical embodiment of the invention is represented in the accompanying drawings forming a part of this specification, in 30 which similar characters of reference indicate corresponding parts in all the views.

Figure 1 is a perspective view of the permutation lock as applied; Fig. 2 is an enlarged longitudinal section of the same; 35 Fig. 3 is an inverted plan view of the same with parts broken out; Fig. 4 is a cross section of the same on the line 4—4 of Fig. 3; and Fig. 5 is a reduced plan view of the lock detached from the part on which it is 40 used.

The casing A of the lock is secured to a part B and the top of the casing A is provided with an elongated slot A' through which extends a spindle C provided at its 45 outer end with a knob C' under the control of the user for turning the spindle C and for moving the same bodily in the direction of the length of the lock. On the spindle C adjacent the knob C' is secured a dial D

provided with a suitable graduation, the 50 marks of which are adapted to indicate on a pointer E forming part of the top plate of the lock casing A. The spindle C extends through a slot F' formed lengthwise in the locking bolt F arranged on the under side 55 of the top of the casing A and provided with a pin F² pressed on by a spring F³ attached to the casing A and serving to hold the bolt F normally in shot-out or locking position. The forward end of the bolt F is 60 adapted to be engaged by a keeper G attached to or formed on the free end of a hasp G' pivoted on a bracket G² secured to the part B' to be fastened to the part B, as plainly indicated in Fig. 1. The keeper G 65 is adapted to pass through an opening A² in the top of the casing A, and the said keeper is provided with a beveled edge G³ adapted to engage the outer end of the bolt F to push the latter rearwardly against the 70 tension of its spring F³ to allow the keeper G to enter the casing A. When this has been done, the bolt F is returned to normal locking position by the action of its spring F³, that is, it engages the keeper G so as to 75 hold the latter in locked position.

The pin F² of the bolt F extends through a slot H' formed lengthwise in a slide H secured to the spindle C to move bodily with the same. The rear end of the slide H is 80 provided with a notch H² and a notch F⁴ in register with the notch H² is formed on the rear end of the bolt F, and both notches F⁴ and H² engage a post I attached to the casing A. By the spindle C being guided 85 in the slot A' and the bolt F and the slide H being guided on the post I, it is evident that the bolt F and the slide H are guided in the direction of the length of the bolt and are thus held 90 against turning movement. The slide H underlies the bolt F and its forward end is provided with a cut-out portion H³ to prevent the keeper G from engaging the slide H and to allow the bolt F to readily 95 engage the keeper.

On the inner end of the spindle C is secured a disk tumbler J and on the said

spindle C between this tumbler J and the slide H are arranged tumblers J' and J² mounted to turn loosely on the spindle C. The tumbler J is provided with a pin J³ extending into segmental slots J⁴, J⁵ formed in the loose tumblers J' and J². The tumblers J, J' and J² are provided at their peripheral faces with notches J⁶, J⁷ and J⁸ adapted to register with each other and to 5 register with the post I to allow of moving the spindle C, the tumblers J, J' and J², the slide H and the bolt F in a rearward direction with a view to retract the bolt F, that is, to move the latter out of engagement 10 with the keeper G. The slots J⁴, J⁵ are of different length so that when the spindle C is turned in one direction its pin J³ travels in the slots J⁴, J⁵ until it reaches one end of the slot J⁴ to carry the tumbler J' along on 15 further turning of the spindle C in the same direction and until the notch J⁷ of the tumbler J' is in register with the post I. The spindle C is now turned in the opposite direction until the pin J³ engages the corresponding end of the slot J⁵ to carry the tumbler J² along until its notch J⁸ is in 20 register with the post I and then the spindle C is again turned in the opposite direction until the notch J⁶ of the tumbler J is in register with the post I. It is understood 25 that this forward and backward turning movement of the spindle C is governed by the combination of the lock and indicated on the dial D by the pointer E. It is further understood that when the tumblers have 30 reached the registering position, the user pushes the knob C' rearwardly to cause the slide H to move rearwardly with the spindle C. This movement of the slide H causes a 35 like movement of the pin F² and consequently of the bolt F to disengage the latter from the keeper G and thus allow of swinging the keeper out of the casing A to the parts B and B'. After the keeper G is 40 disengaged from the bolt F the operator turns the knob C' and then releases the same to allow the spring F³ to return the bolt F and slide H to normal outermost position. The turning of the knob C' moves the notches 45 J⁶, J⁷ and J⁸ of the tumblers out of register with the post I so that the spindle C is held 50 against rearward movement as the peripheral faces of one, two or all of the tumblers abut against the post I and hence prevent 55 backward movement of the spindle C. When the several parts of the lock are in this position the keeper G can be reengaged with the bolt F by swinging the hasp G' into closed position. When this takes place 60 the keeper G pushes the bolt F back against the tension of its spring F³, as previously explained, and when the keeper G has finally entered the casing A the bolt returns to locking position, that is, engages the keeper

G to hold the latter in locked position. It 65 is understood that the bolt F now cannot be retracted unless the lock is set to the proper combination, as previously explained, and hence unauthorized persons cannot surreptitiously open the lock. In order to prevent 70 accidental turning of the loose tumblers J' and J² their peripheral faces are preferably notched and engaged by springs K and K' attached to the guide H so as to move with the same together with the 75 tumblers.

Having thus described my invention, I claim as new and desire to secure by Letters Patent:

1. A permutation lock provided with a 80 spring-pressed bolt normally held by its spring in locking position, mechanism for moving the bolt into unlocking position, the said mechanism having a slide on one side of the bolt and connected therewith to permit the bolt to have limited movement thereon, a spindle secured to the slide for operating it, and means for guiding the bolt, slide and spindle on movement of the parts 85 in the direction of the length of the bolt. 90

2. A permutation lock, comprising a sliding and spring pressed bolt, a slide, means connecting the bolt and slide to permit the bolt to have limited movement on the slide, a spindle secured to the slide, tumblers 95 mounted on the spindle and connected with each other to be operated by the spindle, the tumblers having notches in their peripheries, and a post adjacent the tumblers and with which the notches of the tumblers are 100 adapted to register.

3. A permutation lock, comprising a spindle having a knob, a tumbler attached to the spindle, tumblers loose on the spindle and controlled by the said fixed tumbler, 105 the tumblers having peripheral notches adapted to register with each other, a bolt having an elongated slot through which extends the said spindle, a pin on the said bolt, a spring pressing the said pin, a slide moving with the said spindle and having a slot engaged by the said pin, and a fixed guide post for the said bolt and slide to slide on, the post forming an abutment for the said tumbler notches and the latter when in register being also in register with the said post to allow bodily movement of the bolt, slide and tumblers on moving the spindle in the direction of the length of the bolt. 115

4. A permutation lock provided with a 120 sliding and spring pressed bolt, a slide upon which the bolt has limited sliding movement, a spindle secured to the slide, a tumbler fixed on the spindle and provided with a pin, tumblers mounted loosely on the said spindle 125 and provided with segmental slots engaged by the said pin, the said fixed and loose tumblers having notches at their peripheral

faces, and a fixed post extending across the peripheral faces of the tumblers and adapted to register with the said notches at the time the latter are in register with each other.

In testimony whereof I have signed my

name to this specification in the presence of two subscribing witnesses.

STEPHAN BLAZÉK.
